UNITED STATES PATENT OFFICE

PHILIPP KLAUER, OF NUREMBERG, GERMANY, ASSIGNOR TO THE FIRM VEREINIGTE SCHUHFABRIKEN BERNEIS-WESSELS A. G., OF AUGSBURG-OBERHAUSEN, GERMANY

DESIGN FOR A BABY'S SHOE

Application filed July 8, 1929, Serial No. 31,960, and in Germany March 23, 1929. Term of patent 7 years.

To all whom it may concern:

Be it known that I, PHILIPP KLAUER, a citizen of the German Republic, resident of No. 39 Markgrafenstrasse, Nuremberg, Germany, have invented a new, original, and ornamental Design for a Baby's Shoe, of which the following is a specification, reference being had to the accompanying drawing, forming part thereof.

This invention relates to a baby's shoe with lamb's head printed on the upper, the nose and forehead of the lamb's head plastic by bolstering, projecting movable ears and glass eyes.

The figure is a front perspective view of a baby's shoe showing my new design.

I claim:

The ornamental design for a baby's shoe, as shown and described.

PHILIPP KLAUER.
